UNITED STATES PATENT OFFICE

WALTER L. TURNER, OF PARIS, TEXAS

MECHANICAL COTTON PICKER

Application filed January 2, 1929. Serial No. 329,786.

The present invention relates to an apparatus for picking cotton and has for its prime object to provide a structure which is simple, inexpensive to manufacture, strong and durable, easy to manipulate, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the apparatus embodying the features of my invention;

Figure 2 is a top plan view thereof;

Figure 3 is a transverse vertical section taken substantially on the line 3—3 of Figure 2;

Figure 4 is a longitudinal section through the receptacle taken substantially on line 4—4 of Figure 2;

Figure 5 is an end view of the channel iron with the gearing mounted therein;

Figure 6 is a longitudinal vertical section through one of the picker mechanisms;

Figure 7 is a section taken substantially on the line 7—7 of Figure 6.

Referring to the drawings in detail, it will be seen that the numeral 5 denotes an inverted U-shaped axle mounted on wheels 6 journaled on the ends thereof. A hanger bracket 7 supports an engine 8 from the axle 5. A counter shaft 9 is supported below one end of the axle by means of bearings 10 and is operatively connected with the engine 8 by gearing 11.

A closed receptacle 12 is mounted on the axle 5 and is formed with an upstanding dome or casing 14; that is also closed. The interior of the casing 14 is in communication

with the receptacle through the opening 14' in the top wall of the receptacle and both the receptacle and casing are air tight. A foraminous drum 15 is rigidly secured to the shaft 70, the ends of which are journaled in openings 71 in the opposite side walls of the casing 14 so that the drum will rotate within the casing.

The openings 71 may be made air tight by gland packing nuts of any conventional construction that are not shown in the drawings. The side walls of the casing 14 are continuous or extensions on the side walls of the receptacle and the end walls thereof merge with the top wall of the receptacle about the openings 14'.

The bottom of the casing is opened and registers with the opening 14' of the receptacle. The receptacle is formed with an inclined false bottom 72 adjacent its rear end and the bottom 73 adjacent this false bottom is provided with a slot 61. The false bottom 72 makes the receptacle 12 airtight. The rear end of the receptacle 12 is closed by a tail gate 74 hinged to the top wall of the receptacle at 75.

The tail gate 74 is held in tight engagement with the rear edge of the false bottom 72 by a latch 76. The tail gate 74 is provided with a slot 62 below the false bottom 72 that is aligned with slot 61 to permit the upper run of a belt 60 to pass therethrough.

A suction fan 16 is mounted on the receptacle 12 and the shaft 17 thereof is operatively connected with the counter shaft 9 by a belt and pulley means 18.

A manifold 19 leads from the intake of the suction fan 16 and has a plurality of branches 20 leading into the front of the casing 14. A super-structure includes a pair of bars 21 fixed to the forward upper corners of the container 12 and inclining upwardly and rearwardly and terminating in horizontal rearwardly extending portions the extrem-

ties of which support a transverse channel member 23.

A brace 24 extends between the intermediate portions of the bars 21 and uprights 25 rise from the rear corners of the receptacle upwardly and are fixed to intermediate portions of the bar 21. A plurality of flexible conduits 26 lead from the rear of the casing through loop brackets 27 depending from the channel member 23 and on the ends thereof have picker mechanisms denoted generally by the letter P.

The conduits 26 leading into the interior of the casing 14 through the rear end wall 15 thereof from the picker mechanism P are in alignment with the branches 20 leading from the manifold 19 of the suction fan 16. The rotatable foraminous drum is mounted in casing 14 between the branches 20 and conduits 26 and is rotated by the draft of air passing across the casing between the conduits and branches. The axis of the drum 15 is disposed about and transversely of the path of the current of air flowing through the casing from conduit 26 through conduit 20, so that the air impinging on the lower portion of the drum will cause this drum to rotate.

Each picker mechanism includes a casing formed with side walls 28, a top wall 29, a bottom wall 30, and a rear wall 31. The rear wall 31 is provided with an opening 32 in which is fixed the respective flexible conduits 26. A shaft 35 is journaled in end plates 36 in the ends of the channel member 23 and has a plurality of bevel gears 37 thereon meshing with beveled gears 38 on the ends of flexible shafts 40 journaled through the rear plate of the channel member 23. The flexible shafts 40 extend along the flexible conduits and are 40 journaled in the handle 41 and connected with a shaft 42 in gear casing 43 on the bottom 30 of the picker mechanism P. Two sets of drums are journaled between top 29 and bottom 30 one set to each side of the center of the casing 45 to include forward pairs 45, intermediate pairs 46, and rear pairs 48.

Each drum includes a plurality of disks *a* disposed in spaced relation and having outwardly radiating peripheral fingers *b*. The disks *a* of the drums 46 are larger in diameter than the disks *a* of the drums 45 and the disks *a* of the drums 48 are larger than the disks *a* of the drums 46.

Gears 50 in the case 43 are mounted on the shaft extensions from the drum and have counter gears 51 therebetween in mesh therewith so that all the drums in each series rotate in the same direction. Thus in Figure 6 the upper drums rotate in a counter clockwise direction while the lower drum rotates in a clockwise direction.

The disks *a* of drums 46 are alternately arranged with respect to the disks of drums 45 and 48 as clearly illustrated in Figure 7.

A spiral gear 55 is on the shaft 42 and

meshes with the gears 56 which in turn mesh with the gears 50 on the shaft extensions of the drums 48. The shaft 35 is operatively connected to the fly wheel 60 of the engine 8 by the belt 60 and the upper run of this belt 70 extends through slots 61 and 62.

Suitable one horse draft means or the like 65 is provided on the front of the receptacle so that the machine may be pulled along by a single horse if desired. As the machine is 75 pulled along a plurality of men direct the picker mechanisms P so that the suction shut up through the flexible conduit will draw cotton through the conduit into the casing so as to hit the rotatable baffle foraminous drum 15 so and drop to the bottom of the receptacle.

The fingers D of the front drum first engage the cotton and deliver it to the fingers of the rear drum and the suction pulls in the cotton to the flexible conduit from the casing of 85 the picker mechanism as will be quite apparent.

It is thought that the construction, operation, utility and advantages of this invention will now be quite apparent to those skilled in 90 this art without a more detailed description thereof.

The present embodiment of the invention has been disclosed in detail merely for the purposes of exemplification since in actual 95 practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what 105 I claim as new is:

1. An apparatus of the class described including a wheeled receptacle, a casing on top of the receptacle in communication therewith and forming a part thereof, a suction creating means communicating with the front of the casing, flexible conduits leading from the rear of the casing to provide a current of air through the casing between said conduits and suction creating means, a rotary foraminous 110 drum in the casing disposed in the current of air, the axis of said drum being transverse to and offset from said current of air, and cotton picking mechanisms on the free ends of said flexible conduits.

2. An apparatus of the class described including a wheeled receptacle, a casing on top of the receptacle in communication therewith and forming a part thereof, a suction creating means communicating with the front of the casing, flexible conduits leading from the rear of the casing to provide a current of air through the casing between said conduits and suction creating means, a rotary foraminous drum in the casing disposed in the cur- 115 120 125 130

rent of air, the axis of said drum being transverse to and offset from said current of air, cotton picking mechanisms on the free ends of said flexible conduits, and a superstructure supported on said receptacle for supporting the flexible conduits.

3. An apparatus of the class described including a wheeled receptacle, a casing on top of the receptacle in communication therewith, and forming a part thereof, a suction creating means communicating with the front of the casing, flexible conduits leading from the rear of the casing to provide a current of air through the casing between said conduits and suction creating means, a rotary foraminous drum in the casing disposed in the current of air, the axis of said drum being transverse to and offset from said current of air, cotton picking mechanisms on the free ends of said flexible conduits, a superstructure supported on said receptacle for supporting the flexible conduits, and each mechanism including a plurality of rotatable members having fingers thereon.

25 4. An apparatus of the class described including a wheeled receptacle, a casing on top of the receptacle in communication therewith, and forming a part thereof, a suction creating means communicating with the front of the casing, flexible conduits leading from the rear of the casing to provide a current of air through the casing between said conduits and suction creating means, a rotary foraminous drum in the casing disposed in the current of air, the axis of said drum being transverse to and offset from said current of air, cotton picking mechanisms on the free ends of said flexible conduits, a superstructure supported on said receptacle for supporting the flexible conduits, and each mechanism including a plurality of rotatable members having fingers thereon, and a flexible shaft operatively connected with said rotatable members, gearing, supported on the superstructure and operatively connected with the flexible shaft, a prime mover below the receptacle, and means operatively connecting the prime mover with the gearing.

50 5. A device of the class described including a receptacle, a casing on the receptacle in communication therewith and forming a part thereof, suction creating means communicating with one side of the said casing, flexible conduits leading from an opposite side of the casing to provide a current of air through the casing between said conduits and suction creating means, a rotary foraminous drum in the casing disposed in the current of air, the axis of said drum being transverse to and offset from said current of air, and cotton picking mechanisms associated with said flexible conduits.

60 6. A device of the class described including a receptacle, a casing on top of the receptacle in communication therewith and form-

ing a part thereof, suction creating means communicating with the casing from the front thereof, flexible conduits leading from the rear of the casing to provide a current of air through the casing between said conduits and suction creating means, a rotary foraminous drum in the casing disposed in the current of air, the axis of said drum being transverse to and offset from said current of air, and cotton picking mechanisms on the free ends of said flexible conduits.

In testimony whereof I affix my signature.
WALTER L. TURNER.
